United States Patent Office

Des. 204,542
Patented Apr. 26, 1966

204,542

SILO OR SIMILAR ARTICLE

Erwin G. Dueringer, River Hills, Wis., assignor to
Fibertron Corporation, Cedarburg, Wis., a corpora-
tion of Wisconsin

Filed May 13, 1965, Ser. No. 85,258

Term of patent 14 years

(Cl. D13—1)

Fig. 1

*Fig 2*FIG. 1 is a side perspective view of a silo or similar article, showing my new design.

FIG. 2 is a perspective view of the side of such silo or similar article diametrically opposite the side thereof shown in FIG. 1.

The dominant features of my design reside in the portions thereof shown in full lines.

I claim:

The ornamental design for a silo or similar article, as shown and described.
